DISPLAY MODULE OR SIMILAR ARTICLE

James H. Karlin, Streamwood, Ill., assignor to
Motorola, Inc., Schaumburg, Ill.

Filed Nov. 22, 1974, Ser. No. 526,185

Term of patent 14 years

Int. Cl. D14—02

U.S. Cl. D26—5 C

FIG. 1 is a front perspective view of a display module or similar article, showing my new design;

FIG. 2 is a front elevational view thereof;

FIG. 3 is a left side elevational view thereof; and

FIG. 4 is a rear elevational view thereof.

I claim:

The ornamental design for a display module or similar article, substantially as shown.
